UNITED STATES PATENT OFFICE

ELVIN H. JOHNSON, OF WINNETKA, ILLINOIS

BUILDER'S HARDWARE

Application filed January 23, 1930. Serial No. 422,696.

This invention relates to builder's hardware, and includes among its objects and advantages, the development of a compact and serviceable door holder of the type commonly mounted on the floor, that may be made up either semi-automatic or completely automatic in its action by a minor change in the shape of the latch only.

In the accompanying drawings:

10 Figure 1 is a plan view of a completely automatic door holder according to the invention;

Figure 2 is a section on line 2—2 of Figure 1;

15 Figure 3 is a fragmentary detail, illustrating the form of latch for semi-automatic or convertible operation.

In the embodiment of the invention selected for illustration, the door 10 is provided with a hook member 12 fastened in place by the wood screws 14.

The support 16 for the latch 18 is mounted on the floor by means of the pedestal 20 receiving a central lag screw at 22 and secured against rotation by the wood screw 24.

The latch 18 is apertured at 26 to receive the hook 12 and operates by gravity to engage and to release the hook. For this purpose the hook is provided with a single cam surface at 28 on which the outer bail 30 of the latch member may ride up to permit the hook to enter and be retained in the position illustrated in Figures 1 and 2.

To release the parts, the door may be given a slight additional outward displacement, which will bring the cam surface 28 against the cam surface 32, which defines the inner edge of the aperture 26 and extends downward and inwardly from said edge. This engagement will toss the latch upward to a considerable height and there will be ample time for the door 10 to move away and carry the hook 12 beyond the reach of the bail 30 before the latch falls again.

The supporting plate for the hook 12 is extended downwardly at 34 to provide a metal abutment for the end of a plunger 36 housed in the bore 38 of the support 16.

50 The outward movement of the plunger is

limited by the enlarged head 40 and the end of the bore 38, and the compression spring 42, held in place by the sealing plug 44, resiliently urges the plunger 36 and through it the door 10 away from the support 16 as far as the position determined by the end of the travel of the plunger 36 which is a position where the hook 12 is withdrawn far enough to prevent the bail 30 from catching it.

In the completely automatic construction of Figures 1 and 2, the latch is provided with a heel 46 to limit its upward movement by engaging the surface 48 of the support 16. This surface constitutes the bottom of a housing groove completed by the side walls 50 which house and protect the latch. The surface 48 also functions by engagement at 52 with the continuation of the cam surface 32 to hold the latch in the position of Figure 2 when the hook has been withdrawn.

In the convertible or semi-automatic construction of Figure 3, contact at 52 is retained, but the heel 46 has been omitted from the latch casting so that the latch can be thrown over into the entirely inoperative position indicated in dotted lines at 54. In this construction it is a simple matter to proportion the parts and the strength of the spring 42 in such a way that there is an ample margin for releasing the hook by movement of the door 10 without throwing the latch high enough to cause it to fall back into the position at 54 rather than forward into operative position. However, since the bail 30 projects a trifle out of the housing defined by the walls 50 it is an easy matter for the user to throw or kick the latch back into the position 54 or forward again into operative position.

When the latch is in the position 54 the device still functions as an ordinary bumper to prevent injury to the door when it is swung wide open.

Without further elaboration, the foregoing will so fully explain my invention that others may, by applying knowledge current at the time of application, readily adapt the same for use under various conditions of service.

I claim:

1. A support, a latch pivoted on said support, a hook for engaging said latch, said hook and latch having cooperating cam surfaces for lifting the latch over the point of the hook to interlock the parts, and cam surfaces for throwing the latch clear of the hook upon further inward movement of the hook, said cam surfaces comprising two spaced surfaces on said latch and a single surface on said hook; said latch and support having cooperating portions for holding said latch in position to be engaged by said hook, or thrown back out of the way and inoperative, said support housing all but the outer tip of said latch in both positions, and resilient plunger means acting generally parallel to the movement of said hook and housed in said support, and tending to push said hook away from said support beyond the position for interlocking engagement with said latch.

2. A support, a latch pivoted on said support, a hook for engaging said latch, said latch and support having cooperating portions for holding said latch in position to be engaged by said hook, or thrown back out of the way and inoperative, said support housing all but the outer tip of said latch in both positions.

3. A support, a latch pivoted on said support, a hook for engaging said latch, said latch and support having cooperating portions for holding said latch in position to be engaged by said hook, or thrown back out of the way and inoperative.

4. A support, a latch pivoted on said support, a hook for engaging said latch, said support having a groove housing said latch, said latch having portions contacting the walls of said groove to limit the movement of the latch, said portions permitting said latch to swing back into an inoperative position.

5. A support, a latch pivoted on said support, a hook for engaging said latch, said support having a groove housing said latch, said latch having portions contacting a wall of said groove to limit the movement of the latch, said portions permitting said latch to rise and engage the hook but not to swing back into an inoperative position.

6. A pedestal support having a head provided with a groove comprising side walls and a bottom surface, a latch pivoted on said side walls and between the same, a hook for engaging said latch, said hook and latch having cooperating cam surfaces for lifting the latch over the point of the hook to interlock the parts, a portion of said latch engaging the bottom surface for holding the latch in position to be engaged by said hook, and a lug carried by the latch for engaging the bottom surface for limiting the movement of the latch.

7. A pedestal support having a head por-

tion provided with a groove comprising side walls and a bottom wall, a latch pivoted on said side walls and between the same, a hook for engaging said latch, said hook and latch having cooperating cam surfaces for lifting the latch over the point of the hook to interlock the parts, and cam surfaces for throwing the latch clear of the hook upon further inward movement of the hook, said cam surfaces comprising two spaced surfaces on said latch and a single surface on said hook, said latch having a portion arranged for engaging the bottom surface for holding the latch in position to be engaged by said hook, and a lug carried by said latch for engaging the bottom wall to limit the movement of the latch.

In testimony whereof I hereunto affix my signature.

ELVIN H. JOHNSON.
